(57) **CLAIM**

The ornamental design for a vaporization device, as shown and described.

DESCRIPTION

FIG. 1 is a side perspective view of a vaporization device showing a first embodiment of the new design; FIG. 2 is a top (and identical bottom) view of the design of FIG. 1;

FIG. 3 is a left side (and identical right side) view of the design of FIG. 1;

FIG. 4 is a front view of the design of FIG. 1;

FIG. 5 is a rear view of the design of FIG. 1;

FIG. 6 is an exploded side perspective view of the mouthpiece component, the cartridge component, and the battery component of the first embodiment of the vaporization device;

FIG. 7 is a side perspective view of the mouthpiece component of the first embodiment of the vaporization device; FIG. 8 is a top view of the mouthpiece component of the first embodiment of the vaporization device;

FIG. 9 is a bottom view of the mouthpiece component of the first embodiment of the vaporization device;

FIG. 10 is a left side view of the mouthpiece component of the first embodiment of the vaporization device;

FIG. 11 is a right side view of the mouthpiece component of the first embodiment of the vaporization device;

FIG. 12 is a front view of the mouthpiece component of the first embodiment of the vaporization device;

FIG. 13 is a rear view of the mouthpiece component of the first embodiment of the vaporization device;

FIG. 14 is a front view of the mouthpiece component of a second embodiment of the vaporization device, the only difference with the first embodiment being the racetrack-shaped aperture of the mouthpiece component, it being understood that all other surfaces of the second embodiment are the same as those of the first embodiment;

(Continued)

FIG. 15 is a rear view of the mouthpiece component of the second embodiment of the vaporization device, the only difference with the first embodiment being the racetrack-shaped aperture of the mouthpiece component, it being understood that all other surfaces of the second embodiment are the same as those of the first embodiment;

FIG. 16 is a side perspective view of the cartridge component of the first embodiment of the vaporization device; FIG. 17 is a left side (and identical right side, top, and bottom) view of the cartridge component of the first embodiment of the vaporization device;

FIG. 18 is a front view of the cartridge component of the first embodiment of the vaporization device;

FIG. 19 is a rear view of the cartridge component of the first embodiment of the vaporization device;

FIG. 20 is a side perspective view of the battery component of the first embodiment of the vaporization device;

FIG. 21 is a left side (and identical right side, top, and bottom) view of the battery component of the first embodiment of the vaporization device;

FIG. 22 is a front view of the battery component of the first embodiment of the vaporization device;

FIG. 23 is a rear view of the battery component of the first embodiment of the vaporization device; and,

FIG. 24 is a rear view of the battery component of a third embodiment of the vaporization device, the only difference with the first embodiment being the racetrack-shaped port of the battery component, it being understood that all other surfaces are the same as those of the first embodiment.

The broken lines in the drawings depict portions of the vaporization device that form no part of the claim.

The vaporization device is shown with a symbolic break in its length. The appearance of any portion of the article between the break lines forms no part of the claimed design.

1 Claim, 8 Drawing Sheets
